UNITED STATES PATENT OFFICE.

WILLIAM H. BAKER, OF CHICAGO, ILLINOIS.

ELECTRIC COUPLING AND CIRCUIT-CLOSER.

SPECIFICATION forming part of Letters Patent No. 406,331, dated July 2, 1889.

Application filed March 22, 1889. Serial No. 304,366. (No model.)

To all whom it may concern:

Be it known that I, WILLIAM H. BAKER, residing at Chicago, in the county of Cook and State of Illinois, and a citizen of the United States, have invented a new and useful Improvement in Electric Couplings and Circuit-Closers, of which the following is a specification, reference being had to the accompanying drawings, in which—

10 Figure 1 is an exterior elevation. Fig. 2 is a longitudinal section. Fig. 3 is one of the central cores or plugs detached. Fig. 4 is an end view of one of the completed sections. Fig. 5 is a cross-section on line 5 5 of Fig. 2.

15 The object of this invention is to provide a novel and simple electric coupling and circuit-closer for electric wires of railway-cars, so that it can be readily separated when the cars are uncoupled, and so that in case any 20 one or more cars of a train become detached the engineer will be instantly notified. This is accomplished by means of the device hereinafter described and claimed.

In the drawings, *a a'* indicate the shell or exterior of the device, which is made in two parts and separable at or about the middle. As the two sections are identical in construction, a description of one of them will be sufficient.

25 The shell *a* is provided with a core *b*, which at its inner end is flush with the exterior section, and its outer end projects, as shown, to form a strong attachment of the wire *c* thereto. This core is cut away or grooved, as 30 shown at Fig. 5, to permit of the attachment of the projecting bar *e* on one side and the spring-bar *d* on the opposite side.

The bar *e* is provided with a notch *f*, adapted 35 to receive and engage a corresponding curved projection *g* on the spring-bar *d*, so as to lock and hold the two parts *a a'* together when in use. The spring-bar *d* is also provided with a cross-bar or head *g'*, as shown in Fig. 3, for the purpose of greater certainty in closing 40 the circuit when the sections are separated, which is accomplished by means of the pin *h*, which passes through the core and is permanently attached to or connected with the bar *e*. The bars *d e* are attached to the central core by means of a suitable number of screws, and these attaching-screws *i* and *j* may also be used as binding-posts; but sepa-

rate binding-posts may be supplied, if desired.

When the sections are together, as shown 55 at Figs. 1 and 2, the bar *e* lifts the bar *d* away from the pin *h*, so as to break the cross-connection and leave the main connection of the wires through the coupler perfect or unbroken.

60 Whenever the sections *a a'* are either designedly or accidentally separated, the spring-bar *d* will drop into connection with the pin *h*, and thus complete a circuit through said pin and ring the alarm-bell carried by the engine, it being understood that the wires *c* are carried over the top of the car and connected with the alarm apparatus on the engine in the usual manner; and it will be also understood that the wires *c* have the usual branches 65 connecting with its circuit-breaker, which is operated by the conductor's bell-cord in the usual manner. The device here shown does not change the ordinary operation of these parts, it being for the purpose of making a 70 ready connection of the wires already upon each car and to furnish a means for their ready and safe detachment when the cars are separated accidentally or by design, as the sections *a a'* will separate before producing 75 any excessive strain upon the wires connected with each end of the car, and as the two are alike it is immaterial which end of the car is in advance or toward the engine.

80 When the parts are connected, the spring-bar *d* is lifted out of contact with the pin *h*, and there is sufficient spring-pressure to hold the two parts together by means of the notches and projections *f g*. When they are separated, the spring-bar *d* drops into contact with 85 the pin *h*, so as to short-cut the circuit at that point and give the necessary alarm in case of their accidental separation.

90 The shell or exterior cylinder is best made of hard or vulcanized rubber, and the core 95 may be made of the same material or of wood, and the bars are ordinarily made of brass; but any of the various materials used in the construction and operation of this class of apparatus may be used.

I do not broadly claim an electric coupling comprising two sections each having a core, spring-plates, and metallic strips having contact-pins. My invention differs from the

prior devices in that the spring-bar of each section serves to lock the sections together and also to make the connection with the pin and close the circuit when the sections are separated, thereby dispensing with independent spring-latches.

What I claim as new, and desire to secure by Letters Patent, is—

1. An electrical coupling and circuit-closer for electric wires of cars, consisting of two similar shells $a a'$, each comprising the core b , having the conducting-pin h passing transversely through it, the projecting bar e , secured to one side of the core and having a notch f , and the spring-bar d , secured to the opposite side of the core and having a projection g , for engaging a notched bar, said spring-bar serving to lock the coupling-sections together and also to rest upon and make the electrical connection with the pin when the sections are separated, substantially as described.

2. An electric coupling and circuit-closer for electric wires of cars, consisting of two similar shells $a a'$, adapted to abut at their adjacent ends and each comprising a central core b , having its opposite sides longitudinally cut away or grooved and terminating flush with the inner end of its shell, an oblique conductor-pin h , passing transversely through the core, the bar e , secured in one cut-away or grooved side projecting beyond the core and provided with a notch f , and the spring-bar d , secured in the cut-away or grooved part of the core directly opposite the notched bar, serving to rest on the conductor-pin to close the circuit, and having the projection g to engage a notched bar, substantially as described.

WILLIAM H. BAKER.
